WINDOW FRAME AND SASH ASSEMBLY

Joseph Sylvan, Berkley, Mich.

Application March 23, 1950, Serial No. 151,378

4 Claims. (Cl. 160—90)

1

This invention relates to an improved window frame and sash assembly.

An object is to provide a window frame assembly which is formed completely of sheet metal parts secured together to make an all metal window frame that may be mounted within an opening in a building designed to receive the same and which frame carries a plurality of sash elements mounted therein for vertical slideable movement and so constructed and disposed within the frame as to be capable of removal or replacement therein from one side and to be interfitted in engagement with each other and with parts of the frame structure to provide a weather-tight joint throughout.

Another object is to provide a combined window frame and sash construction wherein the sash guides provided on the frame are formed by strips of sheet metal suitably secured to the frame to constitute vertical guideways for the slideable sash and which are so constructed that the sash may be individually removed from the guide channels upon the inside of the building, but the sash are held at all times securely against removal outwardly and against accidental displacement and a weatherproof joint is formed between the sash and the frame and between cooperating sash elements.

More particularly, the window guide channels formed by the guide strips exhibit a continuous outer guide channel wall which extends from top to bottom of the frame while the inner wall of the channel guide is divided into upper and lower portions separated substantially midway of the height of the window providing a gap at such point through which sash elements may be moved for insertion into the guide channel or withdrawal therefrom.

A meritorious feature is that the construction embodies a guide channel which exhibits throughout its upper portion a width sufficient only to receive a single sash element, while it exhibits throughout its lower portion a width sufficient to receive two sash elements side by side. The combined window frame and sash structure shown herein includes three sash elements slidably mounted within the frame. Two of the sash elements shown are window sash and the third sash element is a screen sash. It is possible with the construction illustrated to dispose the two window sash in superimposed relationship with one serving as a lower sash and the other serving as an upper sash and with the screen stored either in an elevated position or allowed to remain alongside of the lower win-

2

dow sash. It is also possible to change this combination by elevating the lower window sash to an elevated stored position and placing the screen underneath the upper sash for ventilation.

- 5 A meritorious feature exhibited in the sash elements is that the upper and lower sash rails are grooved lengthwise of the rails so that the upper and lower sash will interfit with each other when one is disposed above the other and the upper sash element will slightly overhang the lower one so as to form a weather-resistant joint. The grooving or these sash elements also cooperates with the construction of the window frame assembly itself in certain positions. A sash element disposed in the lower position is mounted with the groove of its bottom rail nested over a ledge extending lengthwise of the sill of the frame assembly while its upper rail is interfitted with the bottom rail of a superimposed sash. 10 The upper ends of the lower portions of the inner guide walls are adapted to serve as supports to be received within the groove of the lower rail of a sash disposed in the elevated stored position to maintain said sash in such position. 15 The window frame assembly exhibits a header portion which is in the form of a downwardly open channel that is relatively deep so that the top rail of a sash element may remain within the channel though the sash element is adjusted vertically within limits. In addition, this header channel is of sufficient depth that a sash element may be raised thereinto to a position of complete disengagement with another sash element disposed therebelow. 20 Other objects, advantages and meritorious features will more fully appear from the following description, claims and accompanying drawings, wherein

- Fig. 1 is an outside elevation of a window frame and sash assembly embodying the invention, 40 Fig. 2 is an inside elevation of a window frame and sash assembly embodying the invention, Fig. 3 is a horizontal sectional view taken on the line 3—3 of Fig. 1, 45 Fig. 4 is a horizontal sectional view taken on the line 4—4 of Fig. 1, Fig. 5 is an enlarged fragmentary perspective of the meeting rail portions of the sash and a jamb member within which they are disposed, 50 Fig. 6 is a fragmentary perspective of the lower outer corner of two sash elements and their engagement with the sill and jamb at such corner, Fig. 7 is a vertical sectional view taken on the line 7—7 of Fig. 1, showing a screen sash disposed underneath the upper window sash and the

lower window sash disposed alongside the screen sash.

Fig. 8 is a vertical sectional view taken on the same line as Fig. 7, but showing the lower window sash disposed in an elevated stored position and the screen sash disposed below the upper window sash, and

Fig. 9 is a vertical sectional view taken on the same line as Fig. 7 showing the manner in which the screen sash may be removed from the assembly.

In the drawings the window frame and sash assembly is shown as mounted within a window opening wherein certain parts of the building adjacent the opening are illustrated in dotted outline, as follows: A sill portion is indicated as 28, a header portion as 22, and opposed complementary jamb portions as 24. In a copending application of the same inventor, filed of the same date herewith, Serial No. 151,377, the particular construction of the frame and specifically the manner in which it is adaptable to fit window openings of slightly different size or slightly out of plumb relationship is illustrated and claimed. This case relates to the combination of the frame and sash structure.

The frame itself is formed of sheet metal parts, as more particularly described in the copending application above referred to. There are complementary opposed jamb portions 26 which in cross section are in the form of outwardly open channels each exhibiting an inner folded side wall 28 that rests against the jamb face of a jamb part of the building. Each channel also exhibits an outer side wall folded upon itself and indicated by the numeral 30. This outer side wall is of greater width than the inner side wall and, as shown particularly in Figs. 3 and 4, overlaps the building wall adjacent the window opening.

The outer side wall of each jamb channel is so fabricated as to exhibit an inwardly projecting flange portion 32 which is continuous therewith and with the bottom of the channel and is disposed in approximately the same plane as the outer wall 30 and constitutes an outer guide wall of a sash guide channel, as shown particularly in Figs. 3, 4, 5 and 6. This outer guide wall 32 extends for substantially the height of the window frame. Each jamb portion is provided with an inner guide wall and this inner guide wall is divided into upper and lower portions. The lower portion of each inner guide wall is shown in the form of a flat metal strip 36 held between the folded over margin 28 of the inner side wall of the jamb channel, as shown particularly in Figs. 4 and 6. As illustrated in Fig. 4 and as particularly set forth in the copending application supra, this strip may be held in place by indentations 40 in the thin sheet metal.

The upper portion of each inner guide wall is in the form of a strip of sheet metal fashioned into angular shape, as shown particularly in Figs. 3 and 5. Each such angular strip has one marginal portion 42 which is received between the lower part of the folded over flange 28 of the inner side wall of the jamb channel and held therein by indentations 40, as heretofore described. This angular upper inner guide wall has another portion 44 which rests directly upon the jamb face of the window jamb element and has a marginal portion 46 that is disposed substantially normal to the portion 44 and constitutes the guide wall proper for the sash channel guide and cooperates with the outer guide wall 32 to establish this guideway for the sliding sash.

These jamb portions of the window frame have their upper ends seated within and secured within a downwardly open header channel 50, as shown particularly in Figs. 7, 8 and 9 and also Figs. 1 and 2. This header channel has its inner wall of greater width than its outer wall and the lower margin is bent as at 52. To mount this structure against the header of a window opening, a channel part 54 is secured by nails or the like to the header of a window opening and is capable of receiving the header 50 of the window frame assembly and retaining the same snugly therein, as shown particularly in Figures 7, 8 and 9.

The sill portion of the window frame assembly is illustrated particularly in Fig. 6 and includes an upwardly open sheet metal channel 58. The lower ends of the jamb portions are seated within this channel and secured to the side walls thereof. To complete the sill portion there is a second sill channel part 60 which telescopes downwardly over the side walls of the sill channel 58 and is disposed between the jamb portions of the window frame.

To complete the sill assembly and to provide for limited adjustment of the frame at the sill within a window opening there is provided a sill plate 62 which is slidably received between the overlapping outer side walls of the two sill channels 58 and 60, as illustrated particularly in Figs. 6, 7 and 8. The ends of this plate 62 are folded as at 64 over the outer margin of the outer side wall 38 of the jamb channel, as illustrated in Figs. 2 and 6. This jamb plate is adjustable vertically. In Fig. 6 the dotted line shows a lowered position. It is adjustable so that its outwardly flanged margin 66 may rest upon a sloping face of a sill part of a window opening.

The said assembly also includes a weatherstrip part which is seated over and held in place upon an upwardly projecting flange stop 68 of the sill channel part 60. This upwardly projecting flange 68 is formed integrally with the sill 60 and lies approximately within the plane of the inner side wall of this sill channel 60. It constitutes an inner stop for a sash element when lowered. It also constitutes a seat for the sill weatherstrip element 70. This weatherstrip element 70 is seated over the stop part 68, as shown in Figs. 6, 7, 8 and 9. It grippingly engages the stop part 68 so as to maintain its position thereover. This weatherstrip 70 has a portion 72 that seats upon the sill face of the sill portion of the window frame. It also has a marginal portion 74 that is turned upwardly so as to constitute a seat for a sash element disposed in the lowered position, as shown in Figs. 6, 7 and 8.

This marginal portion 74 is disposed outwardly from the sash stop 68 a distance greater than the thickness of one of the sash mounted within the window frame. The sash mounted within the window frame are shown as of uniform thickness. The width of this spacing of the flange 74 from the sash stop 68 is, however, less than the thickness of two sash elements and less than the width of the sash guide channel at the bottom by approximately one half of the thickness of a sash element. In other words, as shown in Figs. 6 and 7, a screen sash identified as S and the bottom rail of a lower window sash identified as L are mounted side by side within the lower part of the sash guide channel and the screen sash is seated upon the upturned flange 74. This forms a weatherseal. The construction is such also that

the screen sash is held against the outer wall 32 of the sash guide channel.

The upper and lower sash rails are provided with grooves 76. As shown in Figs. 6 and 7, the groove in the lower sash rail of the screen is seated over the ledge 74 of the weatherstrip 70. The groove in the upper sash rail of this screen is interfitted, as shown in Fig. 7, with the groove in the lower sash rail of the upper window. This constitutes a weather seal at both places and the window, of course, is sealed at the top because the top rail of the sash element is grippingly held between the outer guide wall 32 and the inner guide wall 44 of the sash guide channel and between the outer side wall of the header channel and the inner guide rail 44. In Fig. 7 the lower window sash is shown in a lowered position alongside of the screen within the lower part of the sash guide channel between the lower sash guide rail 36 and the outer guide rail 32 of the sash guide channel.

This lower sash may be raised to a stored elevated position, as shown in Fig. 8, by elevating the same from the position shown in Fig. 7 to that shown in Fig. 8 and seating the groove of the lower rail of the window over the upper ends of the inner guide walls 32. The upper rail of the elevated window is frictionally gripped in position in the header and the window is securely held in such elevated position. The lower rail of this window sash is provided with a latch or handle part 78 whereby it may be more conveniently manipulated. When it is desired to remove the screen or to replace it with another sash, or to remove all the sash from the window frame, the lower window may be removed directly from the position shown in Fig. 7 or it may be elevated from the position shown in Fig. 8 to disengage its lower rail from the upper ends of the inner lower guide walls and then lowered inwardly of the assembly and removed therefrom, being moved through the gaps between the upper and lower sections of the inner guide rail of the sash guide channels. To facilitate the insertion of the upper end of the elevated stored sash into the header opening, the lower margin of the inner wall of the header channel is bent, as shown at 52. The screen may be removed from the position shown in Figs. 7 and 8 by elevating the upper window sash so as to disengage it from the screen and then withdrawing the screen upwardly and inwardly through the gap between the upper and lower portions of the inner walls of the sash guide channel, all as shown in Fig. 9. The sash elements may be replaced within the assembly frame in the window frame through the gap between the upper and lower portions of the inner walls of the sash guide channels.

What I claim is:

1. A window frame and sash assembly comprising, in combination, a window frame assembly provided with opposed complementary metal jamb portions connected at their upper ends by a downwardly open channel-shaped metal header portion and connected at their lower ends by a metal sill portion, said jamb portions exhibiting opposed complementary sash guide channels, a plurality of sash elements vertically slidably mounted within said guide channels, each channel having an outer guide wall continuous from top to bottom thereof and formed integrally with the jamb member and an inner guide wall divided approximately midway of the height of the window providing an upper portion and a separate lower portion, said portions being strips inde-

pendently coupled with the jamb member through having a part of the jamb member folded over a portion of each strip, said portions being separated from each other by a gap having a vertical dimension greater than the transverse dimension of the jamb member and through which a sash element may be moved into or out of the guide channel, the upper portions of the channels having a width capable of receiving a single sash only and the lower portions of the channels having a width capable of receiving two slidable sash side by side, the sill portion of the frame provided with two parallel upstanding ledges extending lengthwise of the sill and spaced apart transversely thereof, the inner ledge having a height substantially greater than the outer ledge, the space between said ledges adapted to receive a sash rail therein and the adjacent part of a sash rail seated upon the outer ledge, said slidable sash having upper and lower rails grooved lengthwise for interfitting engagement, the header channel of the frame having a depth sufficient to permit the upper sash to be elevated thereinto such a distance as to permit disengagement of the groove of its lower rail from the groove of the upper rail of a sash therebelow.

2. A window frame and sash assembly comprising, in combination, a window frame assembly provided with opposed complementary sheet metal outwardly open channel-shaped jamb members connected at their upper ends by a sheet metal header portion and connected at their lower ends by a sheet metal sill member, said jamb members exhibiting opposed complementary sash guide channels, a plurality of sash elements vertically slidably mounted within said guide channels, each guide channel having its outer wall formed by an integral part of the jamb member and being substantially a continuation of the outer wall of the channel of the jamb member inwardly of the window frame, the inner guide wall of each channel being divided into upper and lower guide parts separated substantially midway of the height of the window by a gap through which a sash may be moved into and out of the channel, said lower inner guide wall parts constituting flat metal strips secured to the jamb members by flanges of the inner walls of the channels of the jamb members folded thereover, said upper inner guide wall parts constituting metal strips angular in cross section and seated against the jamb faces of the two jamb members and each having one margin secured to its jamb member by a flange of the inner wall of the channel of the jamb member folded thereover and having its opposite margin projecting inwardly of the frame substantially normal to the adjacent jamb face and offset outwardly of the inner guide wall of the lower part of the sash guide channel, said upper part of the upper sash guide channel adapted to receive therein only a single slidable sash, said lower part of the sash guide channel adapted to receive therein two slidable sash disposed side by side.

3. A window frame and sash assembly, as defined in claim number 2, characterized in that the sill portion of the frame assembly is provided with an upwardly projecting lip extending lengthwise of the sill approximately in line with the lower inner side wall of the guide channel and is also provided with a second upwardly projecting lip extending parallel to the first lip spaced outwardly therefrom a distance in excess of the width of the upper guide channel part and less than the width of the lower guide channel part,

said second lip having a height less than the height of the first mentioned lip.

4. A window frame and sash assembly, as defined in claim number 2, characterized in that the sill portion of the frame assembly is provided with an upwardly projecting lip extending lengthwise of the sill approximately in line with the lower inner side wall of the guide channel, and is formed integral with the upper face of the sill, a supplemental sill member having a part seated grippingly over said lip and having its base part projecting outwardly from said lip overlying the sill face and provided with an outer margin bent upwardly forming a lip of less height than said first mentioned lip and spaced outwardly there-

5 from a distance greater than the thickness of a sash rail seated therebetween.
